UNITED STATES PATENT OFFICE.

FREDERIC A. PEESO, OF PHILADELPHIA, PENNSYLVANIA.

PUNCH.

SPECIFICATION forming part of Letters Patent No. 660,335, dated October 23, 1900.

Application filed March 9, 1900. Serial No. 7,971. (No model.)

To all whom it may concern:

Be it known that I, FREDERIC A. PEESO, a citizen of the United States, residing at Philadelphia, in the county of Philadelphia and 5 State of Pennsylvania, have invented certain new and useful Improvements in Punches; and I do hereby declare the following to be a full, clear, and exact description of the invention, such as will enable others skilled in the 10 art to which it appertains to make and use the same.

My invention relates to hand plate-punches of the class having detachable or interchangeable tools, and is designed particularly for the 15 use of dentists.

The object of my invention is to improve this class of punches by rendering them more efficient, the improvement consisting of means for detachably and adjustably securing the 20 dies or tools to the punch, as will be herein-after more fully explained, and pointed out in the claims.

In the accompanying drawings, Figure 1 is a view in side elevation of a hand plate-punch embodying my invention. Fig. 2 is a view of said punch, showing the outer face of the jaw which holds the female die. Fig. 3 is a vertical central sectional view of the jaws of 25 said punch. Fig. 4 is an end view of the tool 30 or die holder of the punch detached. Fig. 5 represents a group of three male dies or punches of different sizes adapted for use with my improved punch and corresponding female dies, the latter being shown in longitudinal central section. Fig. 6 is a perspective view of a male and a female roughening die or tool. Fig. 7 is a view in side elevation of a male and a female loop die or punch, Fig. 8 being an end view of said male loop die or 35 punch, and Fig. 9 an end view of said female loop die or punch.

My improvements may be applied to hand-punches of any well-known or suitable form. In the present instance I have shown a punch 45 consisting of two members A and B, pivoted together at a and provided with handles A' and B' and also with jaws C and D, which are similarly bowed or curved outwardly. To adapt such a punch to the purposes of my invention, the outer ends of the respective jaws C and D are enlarged into heads C' and D', which are provided with seats or sockets c

and d in alignment with each other. These seats are for the reception of the various tools, which are to be used interchangeably with 55 the punch, one of said seats being adapted for the detachable attachment of perforators of any size, shape, or kind, and the other seat being adapted for the detachable attachment of socket-pieces corresponding to the perforators with which they are to coöperate.

In the present embodiment of my invention the seat c of the jaw C of the punch is screw-threaded for the attachment of a tubular tool-holder E, which is provided with an externally-threaded portion E' for entering the seat c, and also with an exposed flattened or squared portion E², by way of which the tool-holder may be turned. If desired, the tool-holder may be provided with an annular shoulder e. A perforating or punching tool of any desired size or shape, such as F, which consists of a round shank having a head f, is adapted to be placed in the tool-holder E, the head of the tool resting against the inner end 75 of the tool-holder. A set-screw or plug G, screwing into the outer end of the seat c, is employed for securely holding the tool in place by bearing against its head.

The socket-piece H consists in this instance 80 of a tubular shank having a conical portion H', adapted to enter the seat d of the implement-jaw D, which seat is made tapering in order that the conical portion of the socket-piece may be securely wedged in place with- 85 out other fastening.

By means of the construction just described tools of various sizes, shapes, and kinds may be quickly and easily secured to or removed from the punch for performing a 90 wide variety of work. For instance, a set of plate perforating or punching tools of any desired number and having shanks of the same diameter and with operating ends of different sizes may be used. Such a set is 95 illustrated in Fig. 5, in which only three pair of tools are shown, each perforator F having a corresponding socket-piece H. A male perforator F, of any given size, may be quickly inserted in the tool-holder E by first removing the set-screw or plug G and subsequently screwing said plug in place again. A corresponding socket-piece H may be secured in its seat in the opposite jaw by simply forcing

or wedging it in place. The proper position of the perforator and the socket-piece relatively to each other may be secured by screwing the tool-holder in or out to the proper degree and then securely setting or locking it by means of the screw-plug G. The perforator may be detached by simply removing the screw-plug G, while the socket-piece may be detached by tapping its outer end, which projects slightly outside the seat.

Plate-rougheners, such as illustrated in Fig. 6, may also be used with the punch. These consist of a roughening-perforator I, similar to the perforators before described, but having a square point and a corresponding socket-piece I', also similar to those before described, but having a square socket or opening, or a loop-punch, such as shown in Figs. 7, 8, and 9, may be used. The perforator J of this pair of tools is provided with a rounded projection j, adapted to coact with a socket-piece J', having a slot j', corresponding to the projection j of the perforator. The proper relation of the members of these two last-mentioned tools may be secured by placing the socket-piece in any desired position and then forcing the opposing member into place while the same is loosely held, and finally securing said member by means of the screw G, as before explained.

Other tools without limit may be employed with my improved punch; but it is thought that the examples herein shown and described are sufficient to indicate the wide range of usefulness of my invention. My improvements thus obviate the use of a separate

punch or implement for each variety of work to be performed, it being necessary to merely substitute whatever form of tool or set of tools is required.

I claim as my invention—

1. The combination in a punch adapted to hold detachable or interchangeable tools, of the two opposite jaws or members each of which is provided with a socket or seat in alignment one with the other, a tubular tool-holder having adjustable connection with the socket or seat of one of said jaws, a tool adapted to be removably held by said tool-holder, means for securing said tool-holder in any position to which it may be adjusted, and another tool held in the socket or seat of the opposite jaw, whereby the first-mentioned tool may be adjusted toward or away from the opposing tool and firmly locked in position, substantially as described.

2. The combination in a hand plate-punch provided with detachable or interchangeable tools, of a jaw having an internally-threaded seat, a tubular tool-holder having an externally-threaded portion for screwing into said seat, a headed tool adapted to fit in said tool-holder, and a set-screw or plug for screwing into said seat for locking said tool-holder and tool in place, substantially as and for the purpose described.

In testimony whereof I affix my signature in presence of two witnesses.

FREDERIC A. PEESO.
